UNITED STATES PATENT OFFICE.

EZRA DIXON, OF BRISTOL, RHODE ISLAND.

TOP-ROLL SADDLE.

1,189,800.

Specification of Letters Patent.

Patented July 4, 1916.

Application filed March 5, 1915. Serial No. 12,308.

To all whom it may concern:

Be it known that I, EZRA DIXON, a citizen of the United States, residing at Bristol, in the county of Bristol and State of Rhode Island, have invented a new and useful Improvement in Top-Roll Saddles, of which the following is a specification.

This invention relates to certain new and useful improvements in top roll saddles, and 10 the primary object thereof is to provide means whereby the objection of imperfect drawing of certain yarns by reason of failure to relieve the center roll of the weight of the saddle and the tensioning means 15 thereof is obviated.

In mills great trouble is experienced by the reason of the helps' carelessness in moving the back saddle so that when the machine was originally set for the weight on 20 the front roll and the back roll, the weight is through carelessness moved onto the center roll, with the result that imperfect drawing is made for certain yarns.

The present invention briefly proposes the 25 provision of a reversible back saddle, which will obviate the objection noted as the back saddle must be removed and reversed to bring the weight upon the center roll, when such weight is not desired.

30 A further object of the present invention is to provide improved lubricating means for the rolls.

In the drawings—Figure 1 is a vertical sectional view of a part of a spinning machine, showing the present invention applied thereto. Fig. 2 is a central longitudinal sectional view taken through the saddle, and Fig. 3 is a top plan view of the saddle.

The front saddle 1 has the stem 2 provided with a stop lug 3 the latter sliding in and out of slots 4 formed at the lower portions of apertures 5 in lugs 6 that are borne by the bottom saddle 7. The bottom saddle 7 has the usual depending stop fingers 8 the latter being engageable with the bearing of the top rolls *b* and *c*. By reference to the drawings it will be seen that the fingers 8 are positioned closer to one end of the bottom saddle than to the opposite end 50 thereof, thus in effect causing the bottom saddle to have a long and a short end, the purpose of which will be now apparent.

When it is desired to place the weight only on the rolls *a* and *c* after the machine 55 has been running with the weight on all three of the rolls, it is merely necessary to

remove the back saddle from the tail of the front saddle and reverse same, and then replace the back saddle on the tail of the front saddle so as to cause the front saddle to 60 engage with the roll *a* and the back saddle with the roll *c* and throw the weight on said rolls. In Fig. 1 in full lines the saddle is shown engaged with all three of the rolls while in the dotted line position in Fig. 1 65 the back saddle has been reversed and replaced on the tail or shaft 2 of the front saddle and in such reversed position can only engage the roll *c*, due to the provision of the long and short ends of the back saddle 70 as aforementioned.

It will thus be apparent that in one position the back saddle can engage two rolls, and in its reversed position it can only engage one roll, which thus effects the desideratum of preventing the operator from bringing pressure to bear on the center roll to draw certain yarn which does not require application of weight on the center roll, 80 since the short end of the back saddle is incapable of engaging the center roll *b* when the short end of the back saddle points toward the head of the front saddle.

Incidentally the present invention provides means whereby effective lubrication of 85 the back saddle throughout its entire length, and thus necessarily including the short and long end, is had, such means consisting of a wick 9 arranged in a longitudinal channel 10 extending the length of the back saddle 90 7 the channel traversing the fingers 8 so that the latter act in conjunction with a bridge piece 11 to retain the wick against the under face of the back saddle, or in the channel thereof. A duct 12 extends through the top 95 face of the back saddle and communicates with passage 9 so that lubricant may be fed to the wick from above the back saddle.

Having thus described my invention, what I claim as new and desire to secure by Letters Patent is—

1. In a top roll saddle, a back saddle having a pair of spaced upwardly extending apertured lugs with slots leading into the apertures, a pair of spaced depending fingers 105 on the back saddle adapted to engage on opposite sides of a roll, and a front saddle having a stem slidable in said apertures of the lugs and having a stop movable through the slots and engageable with the lugs to 110 prevent disengagement of the saddles except when the stop registers with the slots.

2. In a top roll saddle, a front saddle, a rear saddle, roll engaging means borne by the rear saddle whereby when in one position the rear saddle will engage one roll and upon endwise reversal of the rear saddle the latter will engage two rolls, and means to connect the saddles and to limit the longitudinal movement therebetween so as to require endwise reversal of the rear saddle 10 when said saddle is to be changed from a one to a two roll engagement and vice versa.

3. In a top roll saddle, a front and a rear saddle, the rear saddle in one position being engageable with one roll and in an endwise

reversed position being engageable with two 15 rolls, and means to connect the saddles and to limit movement therebetween whereby to require endwise reversal of the rear saddle in changing same from a one to a two roll engagement and vice versa. 20

In testimony whereof I have signed my name to this specification in the presence of two subscribing witnesses.

EZRA DIXON.
